[57] CLAIM

The ornamental design for an automatic teller machine cabinet, as shown and described.

DESCRIPTION

FIG. 1 is a perspective view of an automatic teller machine cabinet showing my new design;

FIG. 2 is a front elevational view thereof;

FIG. 3 is a left side elevational view thereof;

FIG. 4 is a right side elevational view thereof;

FIG. 5 is a top plan view thereof, the bottom view thereof is plain and unornamented; and,

FIG. 6 is a rear elevational view thereof.

The broken line showing of environment in FIGS. 1, 2, and 4 is for illustrative purposes only and forms no part of the claimed design.
